ELECTRIC LAMP

Charles Spaeth, Flushing, N. Y.

Application October 7, 1937, Serial No. 167,751

7 Claims. (Cl. 176—38)

This invention relates to incandescent lamps and in one aspect consists in a filament of novel construction designed to provide a light source of highly concentrated brilliancy with a small spread between the leads and which is so shaped and arranged as to obviate the danger of short circuiting in use. The novel filament of my invention may be used advantageously wherever a highly concentrated light source is desired. It has an important field of use in lamps provided with a reflecting surface, or assembled with an external reflector defining a focus or a focal zone within the bulb in which the light source is to be located. In another aspect the invention consists in the combination with a reflecting lamp of a filament having a plurality of parts or branches disposed side by side and connected in series by diagonal cross-over connections.

My invention solves many serious difficulties which arise in the construction and maintenance of reflecting incandescent lamps, particularly those of high wattage. In the first place it is desirable to concentrate the filament so as to locate it with the greatest possible exactitude at or near the focus of the reflecting surface. Heretofore this has required that the leads be located so close together as to create danger of arcing between the leads or between adjacent parts of the filament itself. The practical effect of this difficulty has been to limit reflecting electric lamps in their efficiency.

In accordance with the present invention, however, I am able to maintain a relatively low voltage drop between the leads and between adjacent parts of the filament and still employ a filament arranged in a concentrated pattern, of high wattage and with maximum clearance between the filament and the reflecting coating of the lamp. These desirable results are secured by employing a coiled coil filament having spaced loops or branches arranged in series and cross-connected between their diametrically opposite ends or intermediate points. For example, I may arrange the filament in two V-shaped branches disposed side by side and parallel to each other, supporting one diametrically opposite pair of ends by the lead-in wires and the other pair of ends by supporting wires which are cross-connected by a diagonal connector. Thus the full potential drop occurs across the maximum diametrical dimension of the filament pattern, the potential drop through each branch of the filament comprises only one-half of the total drop through the filament, and the potential drop between oppositely disposed points in the two branches of the filament no-

where exceeds one-half the total potential drop of the filament.

An important advantage of this arrangement of the filament branches and their cross-over connections is that the current in any adjacent branches is in the same direction, with the result that the induced electro-magnetic field surrounding each branch is similar in character and electron flow between them is deflected. This reduces or counteracts the tendency of arcing, particularly in a gas-filled lamp, and so increases the life of the lamp and permits employing a more compact filament design than would be possible if the current flow were in opposite directions, under which conditions of course, the electron flow between the branches would be stimulated and increased with a corresponding increase in the tendency to arc.

An important field of use of my invention is in lamps in which a portion of the bulb or reflector has the shape of a parabola expanded until its focal point constitutes a ring of substantial diameter. Theoretically the most efficient results are obtained by locating the filament so that it coincides with the focal ring of the parabolic reflector. As herein shown, however, the branches of the filament are located symmetrically in the bulb and so that they intersect and occupy a portion of the focal plane of the lamp. This extremely concentrated light source is thus disposed to the best possible advantage with respect to the focus or focal zone of the lamp.

While I have referred to a filament comprising two branches it is entirely practical to arrange the filament in three or more branches connected in series or in series-parallel and arranged so that the potential drop through the system is distributed in the manner already explained. These branches of the filament may be disposed in a single plane or corresponding branches may be located in intersecting planes or the branches may be located at different levels, all as in accordance with the requirements of the service under consideration.

Another feature of the invention consists in a fuse or fuses provided in circuit between two of the filament branches or lead-in wire sections. Lamps of the general type to which this invention relates have sometimes exploded when burned to near the end of their normal life due to the failure of the filament and the formation of an arc drawing an excessive amount of current and generating intense heat in the bulb. The diagonal cross-connection which is characteristic of my novel filament supplies a convenient location for a fuse

and contributes to a novel and compact filament pattern. An advantage incident a filament arranged in a series of branches as herein disclosed is that it is thereby rendered shock-resistant in 5 that the amplitude of vibration of the individual sections is substantially reduced as compared to the amplitude of vibration of a long filament strand. A more durable lamp of longer life therefore results from this characteristic of my novel 10 filament.

These and other features of the invention will be best understood and appreciated from the following description of a preferred embodiment thereof, selected for purposes of illustration and 15 shown in the accompanying drawing in which,

Fig. 1 is a view in elevation of an incandescent lamp, portions being broken away to expose the filament.

Fig. 2 is a wiring diagram of the filament circuit,

Fig. 3 is a view in perspective of the filament and its supports,

Fig. 4 is a wiring diagram of a three-branch filament, and

Fig. 5 is a fragmentary view of a coiled filament wound upon a rectangular core.

While the filament of my invention is in no sense limited to use in a reflecting lamp, I have shown such a filament in Fig. 1 as embodied in a 30 reflecting lamp of the type disclosed in the U. S. Letters Patent No. 2,110,590. The bulb includes a rounded end portion 10 which is clear and which transmits the beam of the lamp. This merges into the parabolic portion 11 which in turn 35 merges in the enlarged globular portion 12, and this into the neck 13. The portion 11 is a parabola of revolution expanded laterally until its focal point described a circle of substantial diameter or a focal ring and it is in this ring that 40 the light source should be located for best optical results. The parabolic portion 11 merges into a bulging portion 12 which enlarges the bulb in the vicinity of its light source. The neck 13 terminates in a metal base 14 of usual construction. 45 The lamp is provided with an internal coating of silver or other reflecting medium which extends substantially from its line of maximum diameter to a line in the neck of the bulb and has the effect of concentrating all the light of the lamp 50 and directing it outwardly in a defined beam. A reflecting disk 16 which surrounds the lead wires and is located just beneath the enlarged globular portion 12 of the bulb, cooperates with the walls 55 of the bulb as a reflector, and also acts as a shield to protect the mount from the intense heat generated in the lamp.

The filament, shown in the lamp of Fig. 1 as constituting one desirable embodiment of the invention, comprises two coiled coil filament branches or sections 21 and 22. The filament is disposed with corresponding branches in parallel relation, that is, the axes of the each pair of branches lie in intersecting planes. The general location of the filament branches coincides as 60 nearly as possible with the focal ring of the reflecting surface and they are symmetrically disposed with respect to its plane, that is, the apex of the filament branches 21 and 22 projects above the plane of the focal ring about as much as the 65 outer ends of the filament branches extend below it. The lead wires 17 and 18 sealed in the press of the mount 15 project upwardly and support diagonally opposite ends of the branches 21 and 22. In Fig. 2 the lead wire 17 is shown as 70 connected to the left end of the branch 21 and the 75

lead wire 18 as connected to the right end of the branch 22. The other ends of the filament branches are positioned by supporting wires 19 and 20 as best shown in Figs. 2 and 3. From this it will appear that the lead wires 17 and 18 are 5 spaced from each other by the maximum dimension of the filament pattern, that is to say, by a diagonal of the rectangle formed by projecting the filament on a plane. The supporting wires 19 and 20 are located at the ends of the other 10 diagonal of this plane pattern. The filament sections are connected in series by a diagonal cross-over wire 25 extending between the supporting wires 19 and 20 at a substantial distance below the coils of the filament. As a result of these 15 connections it will be noted that when the lamp is energized current will flow in the same direction simultaneously in both its sections. Additional supporting wires 23 and 24, which are also sealed in the press of the mount 15, or secured to 20 the disk 16, serve to support the centers of the two filament loops or branches 21 and 22 and are 25 spaced apart from the wire 25.

Referring more particularly to the diagram of Fig. 2 it will be seen that the full voltage drop 25 of the circuit, which may be 120 volts, occurs between the lead-in wires 17 and 18 which are spaced by the maximum distance permitted in the filament pattern. A voltage drop of 60 volts occurs between the two ends of each of the filament 30 branches, and a voltage drop of 60 volts occurs between adjacent ends of the branches. The result is that at no place in the filament pattern is there a maximum drop of potential across a gap sufficiently narrow to invite arcing. A fuse 35 26 may be and is herein shown as being inserted in the cross-over connection 25, and is thus interposed in series circuit between the two branches of the filament.

In Fig. 4 is shown the wiring diagram of a filament divided into three branches 30. In this arrangement the lead-in wires 27 and 28 are located at the diagonally opposite corners of the pattern and support wires 29 carry opposite ends of the outer filament branches and both ends of the 45 intermediate filament branch. Each of the outer filament branches is connected at one end to the intermediate branch by the diagonal cross-over connections 31. One of these is provided with a fuse 32 which is thus directly interposed in series 50 between two of the filament branches. The potential distribution is indicated in Fig. 4, there being a drop of 40 volts through each filament branch and 40 volts between adjacent ends of the respective branches. This arrangement as already explained tends to prevent arcing between the 55 lead wires or between any adjacent portions of the filament.

In Fig. 5 is indicated a shape of filament coil which may be advantageously employed in a 60 lamp having a reflecting lamp such as the disk 16 shown in Fig. 1 and in the same position occupied by the filament branches in Fig. 1. The coil may be formed by winding the coiled coil filament 36 upon an oblong mandrel 35 and in the lamp the 65 coil is disposed in the relation to the reflecting disk suggested by Fig. 5, that is to say, with the major cross-sectional axis of the core perpendicular to the disk. The reason for this is that the disk 16 tends to become more discolored by 70 the deposition of tungsten vapor than the reflecting coating of the walls of the bulb. By disposing the filament as suggested in Fig. 5 a smaller part of the emitted light is directed to the disk than 75 to the reflecting walls of the bulb.

The rectangular section filament may be advantageously employed in lamps having no reflecting disk; where it is desired to direct more light rays into certain selected directions, and especially in lamps assembled with external reflectors defining a focus or a focal zone within the bulb in which the light source is to be located. For example, in a lamp having a parabolic reflecting surface a rectangular section filament 10 may be located with its major axis parallel to the axis of the parabola.

While I have shown in the drawing filaments having branches which comprise each a simple coil, it is contemplated that a series-parallel arrangement of branches may be employed, that is to say, an arrangement in which each branch comprises a pair of coils connected in parallel and each pair connected in series. In my prior application, Serial No. 15,605, filed April 10, 1935, 20 I have disclosed several forms of coiled coil filaments which may be utilized to good advantage in connection with the present invention.

The reflecting coating may be applied to the bulb internally or externally as desired, although 25 the present invention is particularly useful in connection with internally silvered bulbs because it facilitates the provision of ample space between the concentrated filament and the silver coating, thus avoiding overheating of the silver.

30 In some cases, for example in lamps designed to operate on a 220 volt circuit, it may be desirable to employ two or more fuses in the filament assembly. Accordingly a fuse may be provided in each of the designed crossover connections or lead-in wires.

Having thus disclosed my invention and described several embodiments thereof for illustrative purposes, but not in a limiting sense, what I claim as new and desire to receive as 35 Letters Patent is:

1. An electric lamp comprising a bulb, a filament having a plurality of parts spaced laterally from each other, arranged electrically in series and having a diagonal cross connection which 40 includes a fuse.

2. An electric lamp comprising a bulb, a filament therein having a plurality of distinct sections arranged electrically in series, and a fuse disposed in circuit between two of the filament sections.

3. An electric lamp comprising a bulb, a filament therein having two sections of coiled coil wire disposed in substantially parallel relation and disposed in series with a diagonal cross connection between them, and a fuse also disposed 10 between them.

4. An electric lamp comprising a bulb, lead wires and supporting wires projecting upwardly into the bulb in a four-cornered pattern, two upwardly directed V-shaped sections of filament located above the ends of the lead and supporting wires in substantially parallel relation, the lead wires being connected to the filament sections at diagonally opposite ends, and a diagonal cross connection between the supporting wires located 20 below the filament sections and including a fuse therein.

5. An electric lamp comprising a bulb having a reflecting disk in its neck portion, and a coiled coil filament having a substantially rectangular 25 coil section disposed with its major axis directed toward said reflecting disk.

6. An electric lamp comprising a bulb having a reflecting coating upon its side walls, and a coiled coil filament having a substantially oblong 30 coil section disposed with its larger surfaces facing said reflecting coating.

7. A gas-filled electric lamp including in its structure a bulb, and a light source enclosed therein and comprising a plurality of distinct 35 coiled coil filament loops, means for supporting the ends and the centers of the loops in the bulb so that the loops are maintained in parallel relationship, and an electrical cross-over connection between diametrically opposite ends of adjacent loops connected to said end supporting means and remote from the supports for the loop centers and from the ends of the loops.
